UNITED STATES PATENT OFFICE.

THOMAS HENRY WILLIAMS, OF MOUNT CARMEL, PENNSYLVANIA.

MINER'S SAFETY-LAMP.

SPECIFICATION forming part of Letters Patent No. 570,780, dated November 3, 1896.

Application filed November 15, 1895. Serial No. 569,072. (No model.)

To all whom it may concern:

Be it known that I, THOMAS HENRY WILLIAMS, of Mount Carmel, in the county of Northumberland and State of Pennsylvania, 5 have invented a new and Improved Miner's Safety-Lamp, of which the following is a full, clear, and exact description.

The object of the invention is to provide a new and improved miner's safety-lamp which 10 is simple and durable in construction, very sensitive relative to gases in a mine, and arranged to prevent relighting of the lamp by the miner.

The invention consists of certain parts and 15 details and combinations of the same, as will be fully described hereinafter and then pointed out in the claims.

Reference is to be had to the accompanying drawings, forming a part of this specification, 20 in which similar letters of reference indicate corresponding parts in all the figures.

Figure 1 is a side elevation of the improvement with parts in section. Fig. 2 is a plan view of the cup carrying the sleeve-locking device, and Fig. 3 is an inverted plan view of the same.

The improved miner's safety-lamp is provided with a lower cylindrical body part A, from which extend upwardly the rods A', supporting the middle body part A², between which and the body part A is arranged a glass cylinder B, through which pass the rays of light, as hereinafter more fully described.

From the middle body part A² extend upwardly the rods A³, carrying a cap A⁴, between which and the middle body part A² is arranged the usual gauze cylinder C, terminating in a sheet-metal cylinder C' and adapted to be opened and closed by the usual sleeve 40 C², as is plainly indicated in Fig. 1.

The top of the sheet-metal cylinder C' is closed by a netting C³, above which extends a curved shield or cap A⁵, carrying an eye A⁶, connected with a hook A⁷ for suspending the lamp from above. An eye A⁸ is also arranged on the cap A⁵ to suspend the lamp from one side. The parts so far described are the same as those found in the ordinary Davy's safety-lamp.

50 Into the lower body portion A screws the fount D, adapted to contain mineral or other oil, into which extends the lower part of the

wick E, passing through a wick-tube F, supported on the upper end of a chamber D', formed on the top of the fount D and preferably being an integral part thereof. 55

The wick-tube F is provided within the chamber D' with a vertically-disposed slot F², through which extends the pointed arm G' of the wick-raising rod G, extending through a tube D², leading from the bottom of the fount D to the top thereof and within the chamber D', as is plainly indicated in Fig. 1. The lower end of the wick-raising rod G is provided with the usual handle G², adapted to be 60 taken hold of by the operator, so as to turn and push the rod to raise the wick whenever it is necessary.

On the wick-tube F is formed a disk F', resting on the top edge of the side wall of the 70 chamber D and held in place by a cap D³, screwing on the said side wall of the chamber. The upper end of the wick-tube F extends through a sleeve H, having a beveled exterior surface formed near the base with an annular recess H', directly above the bottom of an inverted cup I, formed at its lower edge with an outwardly-extending annular flange I', screwing into an interior thread on the body 75 part A.

The bottom of the inverted cup I is formed with a central opening I², through which passes the base of the sleeve H, the latter being provided at its base with an annular outwardly-extending flange H², resting between the cup 80 bottom and the top surface of the cap D³. The annular recess H' of the sleeve H is adapted to be engaged by the arms J of a spring-rod secured at J' to the top surface of the cup I to securely lock the said sleeve H in place after 85 being introduced from underneath in the opening I².

It will be seen that when the sleeve H is passed upward in the opening I² the wedge-shaped exterior surface of the sleeve presses 90 the spring-arms J apart until the latter come into alignment with the annular groove H' and snap into the same, so as to lock the sleeve in position.

Over the free ends of the spring-arms J extends a transverse rod J², secured at its ends at J³ to the bottom of the inverted cup I, as is plainly illustrated in Fig. 2. On the extreme outer ends of the spring-arms J are formed 100

upwardly-extending handles J⁴ to enable the operator to press the spring-arms apart whenever the cup I is removed from the body A to permit of removing the sleeve H in a downward direction through the opening I².

On the under side of the flange I¹ are secured projections I³, adapted to be engaged by a key, wrench, or like tool, to permit an authorized person to unscrew the said cup I from the body A after the fount D has been unscrewed.

Now it will be seen that when the several parts are in the position illustrated in Fig. 1 the miner can manipulate the wick-raising rod G so as to first turn the same to move the pointed arm G' out of engagement with the wick and then pull the rod G downward and again turn the same to move the arm G' in contact with the wick at or near the bottom of the slot F². By now pushing the rod G upward the wick is raised in the tube F. Now it will be seen that any oil pressed out of the wick while pushing upward with the wick-raising rod G, as just described, will flow down the tube F through the larger opening in the top of the fount D back into the latter without danger of any oil passing to the wire-gauze to cause explosions, as heretofore experienced in the ordinary miner's safety-lamp. It will further be seen that when the miner unscrews the fount D and draws the same downward from the body A then the wick-tube F is caused to slide downward with the fount through the sleeve H, locked in place by the spring-arms J. Now during this downward movement of the wick-tube F in the sleeve the burning wick is extinguished, as the necessary air-supply above is cut off. Should the miner light the wick E after the fount D has been removed, and then attempt to put the fount back into its position in the body A, the light will be extinguished the moment the sleeve F passes with its upper end through the aperture in the cap D³ into the sleeve H. Therefore the miner cannot relight the lamp after he once unscrews the fount D, and consequently he must go to an authorized person having a key for unscrewing the cup I. The authorized person, after unscrewing the cup, presses the spring-arms J apart to remove the sleeve H, which is then on the wick-tube F, after which the projecting end of the wick is lighted. The cup I is then screwed back into position in the body A, and the fount D is screwed in position with the sleeve H passing upward through the apertured bottom of the cup I to be finally engaged by the spring-arms J at the time the fount D is screwed home. Thus it will be seen that when the miner unscrews the fount D the sleeve H remains locked in position on the top of the cup I, and consequently the upper end of the wick-tube F passes down in the sleeve H and the light is extinguished.

Having thus fully described my invention, I claim as new and desire to secure by Letters Patent—

1. A miner's safety-lamp, comprising a

lamp-body, an inverted cup having an aperture in its bottom and formed at its lower end with an outwardly-extending flange screwing 70 into the said body, a sleeve having a beveled or tapered exterior surface and formed with a flange at its lower end to engage the bottom of the cup, the said sleeve extending through the aperture in the cup and adapted to form 75 a passage for the wick-tube, and a locking device held on the cup to engage the said sleeve, substantially as shown and described.

2. A miner's safety-lamp, comprising a lamp-body, an inverted cup formed with an 80 aperture and provided at its lower end with an outwardly-extending flange screwing into the said lamp-body, a sleeve formed with a flange at its lower end to engage the bottom of the inverted cup, the sleeve extending 85 through the aperture and projecting above the top of said cup, a locking device to engage the said sleeve, a fountscrewing into the lower end of the lamp-body and provided with a chamber on its top adapted to extend within the inverted cup and a wick-tube supported by the fount and adapted to pass through the said sleeve, substantially as shown and described.

3. A miner's lamp, comprising a lamp-body, an inverted cup screwing into the said body, 95 a sleeve formed with a flange to engage the under side of the cup, the said sleeve projecting through an aperture in the cup, a locking device to engage the said sleeve, a fountscrewing in the lower end of the lamp-body and provided with a separate chamber on its top adapted to extend within the said inverted cup, a wick-tube supported on the said chamber and adapted to pass through the said sleeve, the said wick-tube being provided 100 within the chamber with a slot to receive the wick-raising device, and an apertured cap closing the top of the said chamber and through which the wick-tube extends, substantially as shown and described. 110

4. A miner's lamp, comprising a lamp-body, an inverted cup formed at its lower edge with an outwardly-extending annular flange screwing into the said body, the said cup being provided with an aperture in its bottom, a sleeve 115 formed with a flange at its lower end to engage the under side of the bottom of the cup, the said sleeve extending through the aperture in the bottom of the inverted cup and projecting above the same, a locking device held on the 120 said cup to engage the said sleeve, a fountscrewing in the lower end of the said lamp-body and provided with a separate chamber on its top, a wick-tube provided with a disk 125 or flange adapted to rest on the top of the said chamber, and an apertured cap closing the top of said chamber and holding the disk or flange on the wick-tube in place, the said flange on the sleeve resting between the top surface of the apertured cap and the under 130 surface of the bottom of the cup, the said wick-tube being adapted to pass through the said chamber, apertured cap, and sleeve, substantially as shown and described.

5. A miner's safety-lamp, comprising a lamp-body, an inverted cup screwing in the lamp-body and provided in its bottom with an aperture, a sleeve having a beveled or tapered 5 exterior surface and formed with a flange at its lower end to engage the under side of the bottom of the cup, the sleeve extending through the aperture and projecting above the cup, and provided with an annular recess located di-
10 rectly above the bottom of the cup when the sleeve is in position, and a locking device, comprising a spring secured to the surface of the cup and provided with arms located at oppo-

site sides of the aperture in the cup, the beveled exterior surface of the sleeve engaging 15 said spring-arms and pressing them apart when the sleeve is inserted in the aperture in the cup, and the annular recess in said sleeve receiving said spring-arms when the sleeve is in position, substantially as shown and de- 20 scribed.
